UNITED STATES PATENT OFFICE.

CHARLES A. LIEB, OF NEW YORK, N. Y.

MOTOR-VEHICLE.

SPECIFICATION forming part of Letters Patent No. 659,078, dated October 2, 1900.

Application filed May 23, 1900. Serial No. 17,712. (No model.)

To all whom it may concern:

Be it known that I, CHARLES A. LIEB, a citizen of the United States, residing at New York, in the county of New York and State of New York, have invented new and useful Improvements in Motor-Vehicles, of which the following is a specification.

My invention relates to motor-vehicles, and has for one object to provide means whereby the motor will be automatically thrown out of operation and the brake applied when the pressure upon the controlling mechanism or the releasing means therefor is relieved.

Other objects of the invention will hereinafter appear, and that which I regard as new will be set forth in the claims.

In the drawings forming part of this specification Figure 1 is a side elevation of a motor-vehicle embodying my improvements. Fig. 2 is a plan view of the same, and Figs. 3 and 4 are perspective views of details.

Like reference-numerals indicate like parts in the different views.

The body 1 of the vehicle is mounted, as usual, upon the rear driving-wheels 2 and the front steering-wheels 3, the same being supported upon springs 4. The steering-post 5 extends down through the platform of the vehicle and has secured to it a crank-arm 6, through which and the pitmen 7 said steering-post is connected to the crank-arms 8 on the axles 9, which carry the front steering-wheels 3. By rotating the steering-post 5 in one direction or the other a corresponding movement is of course transmitted to the steering-wheels 3. For the purpose of providing for the rotation of the steering-post 5 the steering-lever 10 is provided, which is pivoted to the upper end of said steering-post and is capable of an oscillating up-and-down movement thereon. Pivoted to the steering-lever 10 is a vertical rod or bar 11, which is adapted to slide vertically along the steering-post 5 and to enter an opening 12 in a guide-plate 13 for the steering-post, which is secured to the front platform of the vehicle. The opening 12 is so disposed in the guide-plate 13 that when the rod or bar 9 is inserted therein the axles of the steering-wheels 3 will lie in a direct line with each other at right angles to the direction of movement of the vehicle. When it is desired to steer straight

ahead, therefore, the lever 10 will be located so as to hold the rod or bar 11 either in or directly above the opening 12. Secured to 55 the pitmen 7, which connect the crank-arms 6 on the steering-post 5 with the crank-arms 8 on the axles 9, are springs 14, provided for the purpose of resisting the rotary movement of the steering-post 5 and for returning the 60 same to its normal position when the pressure upon the steering-lever 10 is relieved. One end of each of the springs 14 is connected to one of the pitmen 7, and the end is connected to a stationary part of the vehicle. 65 The effect of this construction is this: When the hand is removed or pressure is relieved from the steering-lever 10, the springs 14 automatically return said lever and the parts connected therewith and operated thereby to 70 their normal positions, as shown in Figs. 1 and 2 of the drawings, at which time the rod or bar 11 is brought opposite the opening 12 and drops therein by gravity. In case of accident, therefore—as, for example, in a collision or when the operator becomes disabled and loses control of the steering apparatus—the construction described provides for the automatic return of the steering-wheels to such a position as to guide the vehicle in a 75 direct line forwardly.

Preferably, but not necessarily, mounted in the body 1 of the vehicle is a motor 15 of any suitable form and construction, the same being geared to the rear driving-wheels 2 for 85 the purpose of propelling the vehicle in one direction or the other. The specific means shown by me for connecting said motor with the rear driving-wheels 2 consists of a pitman 16, pivoted eccentrically to a gear-wheel 17, 90 around which passes a belt or chain 18, also passing around a roller or gear-wheel 19 on the axle of the rear driving-wheels. The controlling-valve 20 for the motor 15, by means of which the motor is thrown into operation 95 in one direction or the other or cut off, is connected through the shaft 21 with a controlling-lever 22 within reach of the operator. The said valve 20 is so constructed that when the lever 22 is in its normal position, as shown 100 in Fig. 1 of the drawings, the motor will be cut off, but that when said lever is moved forwardly it will start the motor ahead and when moved rearwardly will reverse the mo-

tor. The said lever 22 is partially inclosed by a plate 23, secured to the side of the body 1 adjacent to the operator's seat. The said plate is provided on its inner surface with a 5 socket 24 for receiving the end of the shaft 21 and with a segmental recess 25 above said socket, in which the lever 22 is capable of movement to a limited degree in both directions. Within the socket 25 are secured two 10 leaf-springs 26 26, normally separated by a block 27, and the lever 21 is provided with a lug or projection 28, which lies between said springs 26. When the lever 22 is moved in one direction or the other, it is done against 15 the action of one of the springs 26, and said spring serves to urge the lever 22 back to its normal position. When, therefore, the pressure is removed from the lever 22, it will be automatically returned to its normal position, throwing the motor 15 out of operation 20 through the action of one of the springs 26. In order to lock the controlling-lever 22 in its normal position, I have provided two co-operating locking-jaws 29 30, fulcrumed, respectively, upon studs 31 32 upon the outer surface of the plate 23. The said jaws are in gear with each other, so as to operate in unison and in opposite directions by means of a tooth 33 on the jaw 29, which meshes with 25 a corresponding notch or groove in the jaw 30. The upper ends of the jaws 29 30 are curved inwardly or toward each other and are adapted to embrace the lever 22 above the plate 23. When, therefore, the locking-jaws 29 and 30 are in the positions in which 30 they are shown in Fig. 1 of the drawings, the lever 22 is locked in its normal position with the motor 15 cut off and can only be operated by releasing the locking-jaws 29 35 and 30 from their engagement therewith. The means shown by me for releasing the lever 22 consists of an arm 34, projecting downwardly beyond the pivot 32 of the jaw 30 and connected through a link 35 with a foot-lever 36, 40 pivotally mounted adjacent to the dash of the vehicle. The said arm 34 is further connected to a strong spring 37, attached to a stationary part of the vehicle. The spring 37 serves to hold the foot-lever 36 in its rearward position and the jaws 29 and 30 in locking engagement with the controlling-lever 22. When power is applied by the foot or otherwise to the upper end of the lever 30, the latter is moved against the action of the spring 45 37 and unlocks the jaws 29 and 30, so as to separate the upper ends thereof from the lever 22. The said lever is now free to be moved in one direction or the other against the action of the light springs 26. The foot-lever 36 is provided with an arm 38, which projects down below the floor of the body 1, and is connected with a strap-brake 39 on the axle of the rear driving-wheels 2. The particular means of connection shown consists 50 of rods 40 41 and a connecting series of links 42. It will be observed that the brake 39 is normally applied through the action of the

spring 37, which tends to normally maintain the upper end of the foot-lever 36 in its rearward position and the lower end of said lever 70 in its foremost position. When, however, the upper end of the lever 36 is pressed forwardly, the brake 39 is released. It will be seen, therefore, that the foot-lever 36 controls the action both of the brake 39 and the 75 controlling-lever 22 for the motor, and the spring 37 tends when the pressure on said foot-lever is relieved to first cut off the motor by returning the lever 22 to its normal position and then apply the brake 39. 80

This construction is one of great importance in motor-vehicles, as it provides in the event of an accident to the operator that the vehicle will be automatically stopped at once 85 by the cutting off of the propelling power and the application of the brake.

In connection with the foregoing parts I have also provided means outside the control of the operator whereby the motor 15 may be cut off, either automatically or otherwise, and the brake applied. The said means consist of a cut-off valve 43 for the motor 15, located between said motor and the controlling-valve 20 and having a crank-arm 44 on the stem thereof, which is connected through the rod or bar 45 with a crank-arm 46 on a horizontally-disposed rock-shaft 47, located at the forward end of the vehicle. The said rock-shaft 47 has secured to it a fender 48, which is normally held in its raised position, as shown in Fig. 1 of the drawings, by a coil-spring 49, secured at one end to the shaft 47 and at its opposite end to a stationary part of the vehicle. The crank-arm 46 on the shaft 47 and crank-arm 44 100 on the cut-off valve 43 are so disposed that when the fender 48 is in its normal or raised position communication between the controlling-valve 20 and the motor 15 is open. When, however, the fender 48 is depressed or moved rearwardly, either intentionally by some one outside the vehicle or by accident, as when an obstruction is met with, the shaft 47 will be rocked and the movement thereof will be transmitted, through the 105 means described, to the cut-off valve 43, and thereby throw the motor 15 out of operation. The said shaft 47 is also flexibly connected with the brake 39 through the disk 50 thereon, the cord or chain 51, the rod or bar 52, and the series of links 53, the latter of which are attached to the rod or bar 41, heretofore referred to. The result of this construction is that when the fender 48 is depressed, cutting out the motor 15, the brake 39 is simultaneously applied. The fender 48 serves as a means outside the control of the operator for stopping the vehicle by cutting off the motor and applying the brake. It will be found of great service in case an obstruction 115 is met with, as above set forth. Also when, as at crossings, a vehicle is observed to be proceeding at too high a rate of speed, a policeman or other proper person may depress the 120

fender by hand for the purpose of slowing down or stopping altogether the progress of the vehicle. At certain times it may also be found desirable for the operator to stop the progress of the vehicle suddenly independently of the springs 37, which are provided for this purpose. In such case I connect to the rock-shaft 47 a supplemental foot-lever 54, which may be depressed to rock the shaft 47, cut off the motor 15, and apply the brake 39. This mode of stopping the vehicle may be quicker in its action than that which depends upon the spring 37.

Having thus described my invention, what I claim as new, and desire to secure by Letters Patent, is—

1. In a motor-vehicle, normally-locked controlling means for the motor, a normally-applied brake, and releasing means for said controlling means and brake.

2. In a motor-vehicle, normally-locked controlling means for the motor, a normally-applied brake, and means for simultaneously releasing said brake and controlling means.

25 3. In a motor-vehicle, normally-locked controlling means for the motor, a normally-applied brake, and foot-operated releasing means for said controlling means and brake.

4. In a motor-vehicle, a normally-locked controlling-lever for the motor, a normally-applied brake, and foot-operated releasing means for said lever and brake.

5. In a motor-vehicle, a normally-locked controlling-lever for the motor, releasing means therefor, and means for returning said lever to its locked position when pressure upon said lever is relieved.

35 6. In a motor-vehicle, a normally-locked

controlling-lever for a motor, releasing means therefor, and means for returning said lever to its locked position, when the pressure upon said releasing means is relieved.

7. In a motor-vehicle, a normally-locked controlling-lever for the motor, foot-operated releasing means therefor, and a spring for returning said lever to its locked position when the pressure upon either said lever or releasing means is relieved.

8. In a motor-vehicle, a normally-locked controlling-lever for the motor, a normally-applied brake, releasing means for said lever and brake, and means for returning said lever to its locked position and applying said brake when the pressure upon said releasing means is relieved.

55 9. In a motor-vehicle, a normally-locked controlling-lever for the motor, a normally-applied brake, foot-operated releasing means for said lever and brake, and a spring for returning said lever to its locked position and applying said brake when the pressure upon said releasing means is relieved.

10. In a motor-vehicle, normally-locked controlling means for the motor, releasing means therefor, a normally-applied brake, and connections between said brake and said releasing means, whereby the actuation of said releasing means simultaneously releases said brake.

In testimony whereof I have hereunto set my hand in presence of two subscribing witnesses.

CHARLES A. LIEB.
